UNITED STATES PATENT OFFICE.

THOMAS S. McCAHON, OF FORT WORTH, TEXAS.

TANK FOR COMBUSTIBLE LIQUIDS.

1,413,043.

Specification of Letters Patent. Patented Apr. 18, 1922.

Application filed June 26, 1920. Serial No. 392,052.

To all whom it may concern:

Be it known that I, THOMAS S. McCAHON, a citizen of the United States, residing at Fort Worth, in the county of Tarrant and 5 State of Texas, have invented certain new and useful Improvements in Tanks for Combustible Liquids; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part 15 of this specification.

This invention relates to new and useful improvements in automatic drain apparatus for oil tanks, etc.; and the object in view is to produce a draining system which will 20 work automatically in draining crude oil, or any combustible liquids, from a burning tank, thereby salvaging the oil which otherwise would be a total loss.

More specifically, the present invention 25 consists in the provision of thermostatically operated means for releasing a trap door in the bottom of a tank to permit the oil to make exit to any suitable location, and in the provision of an automatically releasable 30 fire gate to close the exit after the oil has drained from the tank, and thereby smother and extinguish the flame.

My invention comprises further various 35 details of construction, combination and arrangement of parts which will be herein-after fully described, shown in the accompanying drawings and then specifically defined in the appended claims.

My invention is illustrated in the accompanying drawings, which, with the letters of reference marked thereon, form a part of 40 this application and in which:

Figure 1 is a view in side elevation of a tank, partly broken away to disclose my improvements applied thereto;

Figure 2 is an enlarged detail sectional view in elevation, showing the trap door in an open position;

Figure 3 is a detail view in perspective of a portion of the tank bottom and my improvements applied thereto;

Figure 4 is an enlarged detail view of a thermostatic element;

Figure 5 is a fragmentary sectional view of the upper portion of the tank, showing also certain parts of my invention;

Figure 6 is a detached detail view in perspective of a trap door with a bracket, or hanger, carried thereby;

Figure 7 is an enlarged detached detail view in perspective of a trap door frame;

Figure 8 is an enlarged detached detail view in perspective, partly in section, of a lever stand;

Figure 9 is an enlarged detached detail view of a thermostatic element, or collar;

Figure 10 is an enlarged fragmentary detail view of the trap door frame with trap door hinge hanger fastened to the same; and

Figure 11 is a detail view in perspective of a screened-in frame.

Reference now being had to the details of the drawings by numerals:

1 designates an oil tank adapted to store combustible liquids and having in the bottom thereof an opening normally closed by a trap door 6, hinged at 4 to the surrounding frame of said opening; and 5 designates a calking interposed between the contact portions of the door and the frame, in order to make a liquid-tight joint. Bolted, or otherwise secured, to said door is a bracket, or hanger, 6'.

A lever stand 8 is bolted, or otherwise fastened, to the door frame and has pivotally mounted in recesses 8^b, in upwardly extending lugs 8', a pin 9, projecting transversely through a tiltable lever 10, one end of which is adapted to engage the bracket member, or hanger, 6 in the manner shown in Figures 1, 3 and 8 of the drawings.

A gravity lever 11 is pivotally mounted upon a pin 12, journaled in upward projecting lugs 8^a, 8^a of the lever stand 8 and the short end of said lever engages the adjacent end of the tilting lever 10, serving to hold

the same in the retaining position shown in Figure 1 of the drawings.

A cable 13 is fastened to the long end of the lever 11 and passes over the pulley 14, supported on a bracket 1' near the top of the side wall of the tank, and about a shaft 15, to which is fixed a ratchet wheel 16, mounted upon a bracket member 17, secured to the tank. A pivoted pawl 18 engages the ratchet wheel and holds the same from rotation in one direction.

A thermostatic element 19 (details of which are shown in Figure 4 of the drawings) is made of fusible metal and is adapted to form a fusible link in cable 13. The ends of the cable are threaded through the fusible element 19, and are held in place by the use of a cable clamp at 22, thus holding the levers 10 and 11 in locked relation with each other and with said trap door. Said thermostatic element, made of a fusible metal, will melt at a comparatively low temperature and has reinforcing wires 21 of the shape shown in Figure 4 of the drawings, imbedded in the metal, for the purpose of causing the element to withstand the strain due to the trap door. Said wires are made in two parts so that, when the fusible metal melts, said reinforcing wires will come apart.

A fire door 23 is hinged upon a bracket member 24, which is bolted or otherwise fastened to the gate frame in the bottom of the tank. Said fire door, when closed, forms a tight joint between the fire door and the projecting edge 2 of the gate frame. A cable 26 is fastened at one end to a metallic support 27 and at its other end is fastened a thermostatic fusible collar 26', shown in detail in Figure 9 of the drawings. Said cable 26 is fastened to a projecting member 28 on the inner face of the door frame. Said cable 26 is of such length as will normally hold the gate 23 at the inclination shown in Figure 3 of the drawings, so that, when the collar 26' is fused the door will fall by gravity to a closed position.

Leading from the opening in the bottom of the tank is a drain passageway 30 with a trap 31 therein, and through which the oil makes exit from the tank when the door in the bottom thereof is opened, and which serves as a means for conveying the oil to any place of safety.

The parts, in their normal position, are shown in Figure 1 of the drawings, in which the trap door 6 is closed and sealed, and in the event of the oil in the tank being ignited from any source and commencing to burn, the heat generated in the upper portion of the tank will fuse the metal of the thermostatic element 19, thus permitting the lever-locking member 11 to rock and thereby release the lever 10, whereupon the weight of the oil upon the trap door 6 will cause the

same to swing down to an open position, this movement of the door being permitted, as indicated, by the tilting of the levers 10 and 11 incident to slackening the cable 13. The oil from the tank is siphoned off from the drain passageway 30 with the fire still burning upon its upper surface. After the oil is drained from the tank, the heat incident to the burning of the oil will fuse the collar at 28, thus releasing the cable 26, and the fire gate 23 will close by gravity and smother the flame and prevent any further burninig of the oil which has passed through the bottom of the tank.

Figure 11 of the drawings discloses a screened-in frame which may be placed over the working parts in the bottom of the tank to prevent foreign matter collecting and interfering with the closing of the fire door 23.

What I claim to be new is:

1. The combination with a tank for combustible liquids having an opening in the bottom, of a door held to normally close said opening, a second door, a rigid member located above said second door, a cable passing from said member along the under side of said second door, and a fusible link connecting said cable to a part adjacent the under side of said door.

2. The combination with a tank for combustible liquids having an opening in its bottom, of a door normally closing said opening, fusible means for releasing said door, a second door pivoted relative to and adapted to close said opening, a rigid brace supported above said second door, a cable secured to said rigid brace, a fusible link carried by said cable, and means within said opening for engaging said fusible link to maintain said second door in open position.

3. The combination with a tank for combustible liquids provided with an opening in its bottom, of a closure for the opening, means permitting said closure to open upon a raise of temperature within said tank, a door pivoted relative to said opening, a brace rigidly secured to the bottom of said tank and extending to a position above said door when in open position, a cable secured to said brace and extending along the under side of said door, and a fusible link carried by said cable connected with a part within the opening maintaining said door in open position.

4. A tank for combustible liquids provided with an opening in the bottom, a closure for the opening, means to release the closure upon the raising of temperature within the tank, a second closure for the opening, a fusible member engaged within said opening, and a cable secured to said fusible member and attached to a part maintaining said second closure in open position.

5. The combination with a tank for combustible liquids embodying closures there-

for, cables for supporting said closures in predetermined positions, and a fusible link composed of fusible metal having openings to receive said cable and with wires embedded therein, the extremities of which overlap within the mass of said fusible metal.

6. The combination with a tank for combustible liquids having an opening in its bottom, of a closure for said opening, a

cable arranged to maintain said closure in predetermined position, and a fusible link for said cable constructed as a loop for receiving said cable and having arched wires embedded in the mass of said fusible material, the ends of which overlap.

In testimony whereof I hereunto affix my signature.

THOMAS S. McCAHON.
